UNITED STATES PATENT OFFICE.

FRANK NORTON, OF KANSAS CITY, MISSOURI, ASSIGNOR OF ONE-HALF
TO LOUIS ALLEN, OF NEW YORK, N. Y.

DESIGN FOR A CRAVAT-BOW.

No. 38,650.

Specification for Design.

Patented July 2, 1907.

Application filed May 28, 1907. Serial No. 376,220. Term of patent 7 years.

To all whom it may concern:

Be it known that I, FRANK NORTON, a citizen of the United States, residing at Kansas City, in the county of Jackson and State of Missouri, have invented a new, original, and ornamental Design for Cravat-Bows, of which the following is a specification, reference being had to the accompanying drawing, forming part thereof.

The figure is a perspective view of a cravat bow showing my new design.

I claim:

The ornamental design for a cravat bow, as shown.

FRANK NORTON.
